GOTTFRIED SCHNEIDERS, OF BERLIN-FRIEDENAU, GERMANY, ASSIGNOR TO AKTIEN-
GESELLSCHAFT "EOS," OF GLARUS, SWITZERLAND.

MINERAL-OIL AND CARBOHYDROGEN-GAS EXTRACTING PROCESS.

1,418,098.

Specification of Letters Patent. Patented May 30, 1922.

Original application filed September 2, 1919, Serial No. 321,275. Divided and this application filed August 15, 1921. Serial No. 492,486.

To all whom it may concern:

Be it known that I, GOTTFRIED SCHNEIDERS, a citizen of Germany, and a resident of Heide, Holstein, Germany, have invented 5 certain new and useful Improvements in Mineral - Oil and Carbohydrogen - Gas Extracting Processes, (for which I have filed applications in Germany, Patent No. 305,794, January 15, 1917; Germany, Patent No. 10 319,548, March 15, 1918; Germany, Patent No. 319,549, March 25, 1918; Austria, Patent No. —, May 28, 1918; Hungary, Patent No. 78,398, June 3, 1918; Rumania, Patent No. —, July 5, 1918;) and I do hereby 15 declare the following to be a full, clear, and exact description of the invention, such as will enable others skilled in the art to which it appertains to make and use the same.

20 In the application for Letters Patent (Serial Number 321275) filed Sept. 2, 1919, a process of extracting mineral oil and carbohydrogen gas from oil deposits is described which process consists in making a 25 passage through the porous, bituminous and gaseous deposit with the aid of an air-dam having shutable doors that is shifted into the deposit by hydraulic pressure. When all the oil and gas in the deposit in the 30 neighbourhood of the air-dam has been removed, the doors of the air-dam are opened and the rock is then pressed through the door, the air-dam being shifted forward and the lining of the drive extended as the 35 excavation work proceeds.

By the afore-described process the rock is caused to yield up most of the flowing oil which it contains. But a certain portion of the existing bitumen will be retained by the 40 rock in a manner similar to a sponge, which only yields up a certain surplus of the liquid it sucked up, whilst the remainder secretes itself in the pores of the sponge and makes it damp. This residual bitumen 45 develops each single grain of sand like a thin skin and up to the present it was only possible to separate it from the sand by dislocating the latter and sending it to the surface, where it was boiled in water or broiled 50 in closed vessels.

It is an object of this invention to provide means for subjecting the sand, which is damp with petrol to a preparatory process at the place where the oil is extracted from

the deposit immediately after the oil extracting process explained in the preceding paragraphs is concluded, and to separate the bitumen at the place of the deposit during the removal of the oil-bearing sand. To this end I detach the oil-bearing sand 60 from the deposit by means of a hydraulic jet.

I have illustrated a preferred embodiment of my invention in the accompanying drawing, which is a vertical sectional view 65 of an apparatus embodying my invention.

In the figure i^1 indicates a pump whose pressure pipe q is provided with a nozzle that is passed through the door of the end plate d , or through a slit or a ball joint in 70 the door, into the space h for the purpose of dislocating the sand by washing it away. The liquid squirted through the nozzle consists of cold, or preferably hot, water or 75 solutions of salt such as a lye of magnesium chloride or the like. By the mechanical thermal and dissolving action of the jet, and on account of the friction of the grains of sand against each other, the bitumen is 80 immediately separated from the sand at the place where it is removed from the deposit. The slimes consisting of sand, bitumen and water or another liquid are drawn off from the space h through a suction pipe r by an 85 elevating pump E and forced through a pressure pipe v into a collecting pit w (blind shaft or water-hole) in which the sand settles at the bottom, the squirting fluid at middle height, and the oil at the top. It is 90 advantageous to arrange several collecting pits w so that one may be emptied whilst from another squirting fluid is taken through a pipe x and oil through another pipe, the squirting fluid being returned by the pump i^1 to the place of excavation, whilst the oil 95 is sent to the surface through a pressure pipe z . When one pit is filled and another is emptied and cleaned, the actions of the various suction and pressure pipes are 100 reversed, so that the empty pit is filled and the full collecting pit is emptied and cleaned.

To obtain a still more perfect separation of the bitumen from the sand, the pipe v through which the slimes are drawn from the space h , may be heated by an enveloping steam pipe r^1 through which steam, engine gases or any other heating agent may be sent.

Thus in using my new process it is not necessary to send the sand to the surface. The sand can be freed of the bitumen adhering to it immediately after it is dislodged from the deposit, and used for filling hollow spaces in the mine and for caulking joints.

I claim:

1. The process of removing oil-bearing sand from its deposit and of simultaneously subjecting it to an oil separating treatment consisting in dislodging the sand from its deposit by a jet of fluid so that by the action of the jet and by the friction set up between the grains of sand, said grains are freed of the bitumen which adheres to them.
2. The process of removing oil-bearing sand from its deposit and of simultaneously subjecting it to an oil separating treatment consisting in dislodging the sand from its deposit by a jet of hot fluid so that by the heat and by the action of the jet, and by the

friction set up between the grains of sand, these latter are freed of the bitumen which adheres to them.

3. The process of removing oil-bearing sand from its deposit and of simultaneously subjecting it to an oil separating treatment consisting in dislodging the sand from its deposit by a jet of fluid so that slimes composed of sand and the said fluid are formed, and in sending the said slimes through a heated pipe, so that by the action of the jet, the friction of the grains of sand against each other, and of the heat derived from the heated pipe, the adhesion of the oil to the sand is neutralized and oil made free to collect.

In testimony whereof I affix my signature in presence of two witnesses.

GOTTFRIED SCHNEIDERS.
